**CONTROL FOR FILLING CHANGE MECHANISM
FOR LOOMS**

Howell M. Tate, Cheraw, S.C., assignor to Burlington Industries, Inc., Greensboro, N.C., a corporation of Delaware

Filed July 20, 1965, Ser. No. 473,317
9 Claims. (Cl. 139—242)

The present invention relates to improvements in controls for filling change mechanisms on automatic filling replenishing looms, and more particularly, to an improved electrical and mechanical control system for detecting spent bobbins and initiating actuation of the filling change mechanism.

In looms of the automatic filling or weft replenishing type, for example, the Draper loom, there is provided a magazine for storage of full bobbins or quills, and a filling change mechanism having a control for detecting a spent bobbin and actuating transfer mechanism for transferring a full bobbin into the shuttle box as the spent bobbin is stripped therefrom. Usually this type of loom includes a midget feeler positioned on the box side of the loom for feeling the amount of filling remaining on the bobbin when the shuttle enters the shuttle box. If the midget feeler indicates a spent bobbin, it in turn actuates an elongated starter shaft extending transversely across the loom to the replenishing side, the starter shaft in turn setting up the pivotal hammer so that the hammer can actuate under the influence of the forwardly moving lay to project a full package or bobbin into the shuttle when the shuttle returns to the shuttle box on the replenishing side of the loom, the full bobbin expelling the spent bobbin. The starter or rock shaft was mounted at its ends in bearings and on its end located at the replenishing side of the loom; it was provided with the usual rearwardly extending arm connected to a finger which engaged a pin that in turn was operatively connected to a shuttle feeler on the replenishing side of the loom. The shuttle feeler was moved by the rocking motion of the starting shaft 15 to a position rearwardly of the loom for determining whether or not a shuttle was properly boxed for replenishing. If the shuttle feeler indicated that the shuttle was properly boxed in the replenishing end, then movement of the reciprocating lay would cause the hammer to be rocked about its pivotal axis on a stationary shaft so as to insert a full bobbin or quill into the shuttle while the spent bobbin was expelled downwardly therefrom.

The present invention is an improvement over such prior controls for filling change mechanisms in that it eliminates the transversely extending rock or starter shaft, the expensive bearings supporting the same, the mechanical coupling of the starter shaft to the midget feeler, and the rearwardly extending arm and finger arrangement for moving the shuttle feeler rearwardly into position for determining whether or not the shuttle is properly boxed.

Another object of the present invention is to provide an improved control for filling change mechanism which is part mechanical and part electrical and which can be installed on existing looms as well as new looms.

A still further object of the present invention is to provide an improved control filling change mechanism for looms in which an electrical circuitry is used for initiating activation of linkage controlling the filling change mecha-

2

nism, the electrical circuitry also including means for rendering the linkage inactive should the loom stop at any time during replenishing so that the filling change mechanism is not operated.

Another object of the present invention is to provide a control for a filling change mechanism having a simplified electrical circuitry for initiating actuation of linkage for moving the transfer hammer with means actuated by movement of the transfer hammer to reset the circuitry for the next detection of a spent bobbin.

These and other objects and advantages of the present invention will appear more fully in the following specification, claims and drawings in which:

FIGURE 1 is a diagrammatic view of a loom having the improved control for the filling change mechanism;

FIGURE 2 is a diagrammatic side view of the linkage arrangement actuated by the electrical circuitry in controlling the filling change mechanism;

FIGURE 3 is a diagrammatic view looking from the left of FIGURE 2; and

FIGURE 4 is a view similar to FIGURE 2 but illustrating the parts of the mechanical linkage after detection of a spent bobbin and just as the transfer hammer starts its insertion of a full bobbin to replace the spent bobbin in a shuttle boxed on the replenishing side of the loom.

While this invention is primarily applicable to a "Draper" type of filling replenishing loom, it will be understood by those skilled in the art that the invention is also applicable to other types of replenishing looms where in the loom utilizes a transfer hammer for inserting a full bobbin and stripping a spent bobbin.

Referring now to the drawings wherein like character or reference numerals represent like or similar parts, the automatic replenishing loom of the present invention is diagrammatically represented and generally indicated at 10. It includes the usual box end 12 and replenishing end 14 wherein there is provided a magazine (not shown) for full bobbins and/or equipment such as automatic bobbin winding mechanisms for winding the filling on spent stripped bobbins and supplying such bobbins automatically to the magazine. The loom 10 is further provided with the usual reciprocating lay 16 on which is mounted a shuttle box 18 at the box end 12 and a second shuttle box 20 at the replenishing end 14. The usual picker sticks (not shown) are adapted to pick the shuttle S back and forth across the lay 16 through the shed of the warp controlled by the usual harnesses (not shown).

A midget feeler 22 disposed on the box end of the loom is arranged to feel the filling on the bobbin B of shuttle S each time the shuttle is received in the shuttle box 18. The midget feeler 22 is operatively connected to a normally open switch 24 in a 12 volt alternating current circuit generally indicated at 26. If the bobbin B is spent of filling, the midget feeler will close the switch 24 so as to energize the circuit 26. In more detail, the circuit 26 includes a hot line 28 extending from a source of current 30 to one pole of the switch 24, a second line 28 extending from the other pole of the switch 24 to a relay 30. A third line 31 extends from relay 30 to ground G to complete the circuit 26.

Relay 30 when energized by closing of switch 24 is adapted to close a switch 32 in a holding circuit 34 for the relay. It is necessary to have the holding circuit 34 for the relay 30 as the switch 24 is only momentarily

closed when the shuttle S enters the box 18 and the bobbin B is detected as being spent. As soon as the shuttle S is picked out of the box 18 back to the replenishing side 14 of the loom 10, the switch 24 opens and consequently the relay would be de-energized unless the holding circuit 34 was provided.

A second circuit generally designated at 36 extends from a source 38 of 110 volt alternating current through a solenoid 40 having a core 44 and through a switch 42 also actuated by the relay 30. The circuit 36 extends from the switch 42 to ground G through the line 31. As will now be evident when relay 30 is energized and so long as it is maintained energized by the holding circuit 34, the circuit 36 will also be energized so as to actuate the core 44 of the solenoid 40 upwardly as viewed in the drawings.

Referring now to FIGURES 2, 3, and 4, it will be noted that the solenoid 40 is positioned on the replenishing side 14 of the loom and that its reciprocating core 44 has pivotally connected thereto at 46 one end of a connecting rod 48. The opposite end of the connecting rod 48 is pivotally connected to one end of an L-shaped arm 50 as indicated at 52. The arm 50 is pivotally connected at 54 to an arm 56 extending off of a transfer hammer 58. Transfer hammer 58 is pivoted on a horizontal axis indicated at 60 in the usual manner and is provided with a spring 62 for normally returning it to its inactive position. The transfer hammer 58 usually is journaled for pivoting movement on a stationary shaft 64 suitably supported at the replenishing side 14 of the loom 10.

L-shaped arm 50 is provided at its end opposite to its connection with connecting rod 48 with a rod element or cam follower 66 which extends parallel to but spaced from the shaft 64. The cam follower 66 rests on the top of a cam 68 suitably journaled on the stationary shaft 64, the cam 68 having integrally fixed thereto an L-shaped actuating arm 70 extending generally rearwardly of the loom.

As illustrated in FIGURE 1 and FIGURE 2 (which is the inactive position of the linkage mechanism for controlling actuation of the hammer 58), the actuating arm 70 has its free end 71 extending rearwardly of the loom and is arranged when pivoted upwardly about the axis of shaft 64 to be in a position for engagement with a duckbill 72 or Stafford cutter (FIGURE 4) which is moved when its lay bunter 74 is engaged by a portion of the lay 16 on the forward movement of the same. Of course, the duckbill or Stafford cutter 72 does not move on each forward stroke of the lay, but only moves forward one time upon each transfer of the filling as fully shown in United States Patent No. 1,552,388 issued Sept. 1, 1925 to Alfred E. Stafford.

The actuation of the control thus far described begins when the midget feeler 22 detects a spent bobbin B at the box end 12 of loom 10. This causes the switch 24 to momentarily close thereby energizing the first circuit 26. The relay 30 will be energized closing its switches 32 and 42. Upon closing of the switch 32, the holding circuit 34 through the relay maintains the relay energized even though the switch 24 opens when the shuttle S is picked back across the lay 16 to the replenishing side 14 of loom 10.

The energizing of relay 30 also causes the circuit 36 to be energized so that solenoid 40 is energized to move its core 44 upwardly from the position shown in FIGURE 2. Upon upward movement of the core 44, the connecting rod 46 also moves generally upwardly and since the transfer hammer 58 cannot move at this time, the L-shaped arm 50 is pivoted about its connection 54 on the arm 56 of the transfer hammer 58. As viewed in FIGURE 2, this pivoting of the L-shaped arm 50 will be in the direction of the arrow A and the bar 66 of the arm 50 will push downwardly on the cam 68 so as to also pivot the cam 68 in a counterclockwise direction about its pivot axis 60 on the stationary shaft 64. Cam 68 continues to

pivot in a counterclockwise direction until the rod or cam follower 66 rides over the edge of the cam and lodges on the surface 69 on the end of the cam as shown in FIGURE 4. Upon pivoting of the cam 68, the actuating arm 70 fixed thereto also pivots until it assumes the position shown in FIGURE 4. When the actuating arm 70 assumes the position shown in FIGURE 4, it is in position to cause the transfer hammer 58 to pivot clockwise in the direction of the arrow D of FIGURE 2 when it is engaged by the duckbill 72 moving forwardly as indicated at E. As mentioned above, the duckbill 72 moves forwardly relative to the loom 10 when its lay bunter 74 is engaged by the forwardly moving lay 16 during transfer of the filling. The duckbill 72 engages the end 71 of the actuating arm 70 and pivots it and the cam 68 in a clockwise direction as shown by the arrow C in FIGURE 4. The cam followed 66 which is fixedly connected to the L-shaped arm 50 is moved with the cam 68 in a clockwise direction but since the connecting rod 48 cannot move as the solenoid 40 is still energized, the L-shaped arm 50 swings in a clockwise direction about the pivot point 52 rather than the pivot point 54. This movement causes the transfer hammer 58 to swing in a clockwise direction of the arrow D about the stationary shaft 64.

As the transfer hammer 58 swings downwardly to a position of transfer, it closes a switch 80 in a line 82 paralleling the relay 30, thus short circuiting the relay 30 so that the current through the holding circuit 34 goes directly to ground G instead of through the relay. This causes the relay 30 to be de-energized thus opening the switches 32 and 42 whereby the holding circuit 34 is broken as well as the circuit 36 to the solenoid 40. When the solenoid 40 is de-energized, the core 44 of the same returns downwardly to the position shown in FIGURE 2 which permits the spring 62 to return the hammer 58 to its inactive position as well as permits the linkage to return to its inactive position shown in FIGURE 2.

Loom 10 is provided with the usual knock-off or stopping lever 84. During loom operation the stopping or knock-off lever 84 is normally in a non-stopping or running position such as shown in FIGURE 1. However, as soon as the loom 10 stops for any reason, such as the shuttle S not being properly boxed in the box 20, or breaking of the filling or warp, the stopping lever 84 is pivoted in a counterclockwise direction as viewed in FIGURE 1. Stopping lever 84 is connected to a normally open switch 86 in a circuit 88 parallel to the relay 30 as well as parallel the circuit 82. If the midget feeler 22 has detected a spent bobbin and the relay 30 has been energized to set the linkage mechanism into a position for initiating actuation of the transfer hammer 58, and if the loom stops while the linkage mechanism is in this position, the movement of the lay 16 from inertia will not cause the transfer hammer 58 to insert a full bobbin and eject a spent bobbin as the lever 84 will have short circuited the relay 30 to de-energize the same thus returning the elements of the linkage to the position shown in FIGURE 2 wherein the arm 70 is out of the path of the duckbill 72. Thus a full bobbin will not be inserted into the shuttle until after the cause for stoppage of the loom has been corrected.

The system heretofore described and illustrated diagrammatically in the drawings fully and effectively accomplishes the advantages and objects of the present invention. It will be realized, however, that the foregoing specific embodiments have been shown and described only for the purpose of illustrating the principles of this invention and are subject to some changes without departing from such principles.

Therefore, the terminology used in the specification is for the purpose of description and not limitation, the spirit and scope of the invention being defined in the claims.

What is claimed is:

1. In an automatic replenishing loom having a box side

with a filling detector, a replenishing side having a filling change mechanism including a pivotal hammer for inserting a full bobbin in a shuttle and stripping a spent bobbin therefrom, a reciprocating lay, the improvement in means for controlling the filling change mechanism when the filling detector indicates a spent bobbin comprising: an electrical circuit having a relay therein; a normally open switch in said circuit and operatively connected to the filling detector and closed by the same when a spent bobbin is detected at the box side of the loom, said relay being energized when said switch is closed; a normally open holding circuit for said relay, said holding circuit being closed when said relay is initially energized by closing of said detector switch; a normally open switch mounted in parallel with respect to said relay, said normally open switch being actuated to closed position by movement of said hammer whereby said holding circuit is short circuited so that said relay is de-energized thus causing said solenoid to return said linkage to its inactive position; a second normally open circuit having a solenoid therein and adapted to be closed upon energizing of said relay; linkage means operatively connected to the hammer and to the solenoid, said linkage means being actuated upon energizing of said solenoid from an inactive position to a second position for initiating actuation of the hammer; means movable by the lay and operatively engaging said linkage means when said linkage means is in said second position to thereby move said linkage means on the next pick after detection by said filling detector so as to cause the hammer to insert the full bobbin in the shuttle while stripping the spent bobbin therefrom.

2. In an automatic replenishing loom having a box side with a filling detector, a replenishing side having a filling change mechanism including a pivotal hammer for inserting a full bobbin in a shuttle and stripping a spent bobbin therefrom, a reciprocating lay, the improvement in means for controlling the filling change mechanism when the filling detector indicates a spent bobbin comprising: an electrical circuit having a relay therein; a normally open switch in said circuit and operatively connected to the filling detector and closed by the same when a spent bobbin is detected at the box side of the loom, said relay being energized when said switch is closed; a normally open holding circuit for said relay, said holding circuit being closed when said relay is initially energized by closing of said detector switch; a normally open switch mounted in parallel with respect to said relay, said normally open switch being actuated to closed position by movement of said hammer whereby said holding circuit is short circuited so that said relay is de-energized thus causing said solenoid to return said linkage to its inactive position; means to short circuit said relay whenever said loom is inoperative; a second normally open circuit having a solenoid therein and adapted to be closed upon energizing of said relay; linkage means operatively connected to the hammer and to the solenoid, said linkage means being actuated upon energizing of said solenoid from an inactive position to a second position for initiating actuation of the hammer; means movable by the lay and operatively engaging said linkage means when said linkage means is in said second position to thereby move said linkage means on the next pick after detection by said filling detector so as to cause the hammer to insert the full bobbin in the shuttle while stripping the spent bobbin therefrom.

3. The automatic replenishing loom as claimed in claim 2 in which said last-mentioned means includes a normally open switch in parallel with said relay and switch actuator means movable upon stopping of the loom to close said last-mentioned switch.

4. In an automatic replenishing loom having a box side with a filling detector, a replenishing side having a filling change mechanism including a pivotal hammer for inserting a full bobbin in a shuttle and stripping a spent

bobbin therefrom, a reciprocating lay, the improvement in the filling detector indicates a spent bobbin comprising: an electrical circuit having a relay therein; a normally open switch in said circuit and operatively connected to the filling detector and closed by the same when a spent bobbin is detected at the box side of the loom, said relay being energized when said switch is closed; a normally open holding circuit for said relay, said holding circuit being closed when said relay is initially energized by closing of said detector having switch; a second normally open circuit having a solenoid therein and adapted to be closed upon energizing of said relay; linkage means operatively connected to the hammer and to the solenoid, said linkage means being actuated upon energizing of said solenoid from an inactive position to a second position for initiating actuation of the hammer; means movable by the lay and operatively engaging said linkage means when said linkage means is in said second position to thereby move said linkage means on the next pick after detection by said filling detector so as to cause the hammer to insert the full bobbin in the shuttle while stripping the spent bobbin therefrom; said linkage means including a connecting rod connected at one end to and movable by said solenoid, an arm operatively pivotally connected intermediate its ends to said hammer on an axis parallel to and displaced laterally from the pivotal axis of said hammer, said arm being pivotally connected at one end to said rod, a cam follower carried by said arm at its opposite end, a cam pivoted on the pivot axis of the hammer, and an actuating arm fixed to said cam and movable thereby into the second position for engagement with the means movable by the lay.

5. In an automatic replenishing loom having a box side with a filling detector, a replenishing side having a filling change mechanism including a pivotal hammer for inserting a full bobbin in a shuttle and stripping a spent bobbin therefrom, a reciprocating lay, the improvement in means for controlling the filling change mechanism when the filling detector indicates a spent bobbin comprising: linkage means at the replenishing side of the loom and operatively connected to the hammer, said linkage means being actuated from an inoperative position to a second position for initiating actuation of the hammer, said linkage means including a rod, an arm pivotally connected intermediate its ends to said hammer on an axis parallel to and displaced laterally from the pivotal axis of said hammer, said arm being pivotally connected at one end to said rod, a cam follower carried by said arm at its opposite end, a cam pivotal on the pivot axis of the hammer, and an actuating arm fixed to said cam and movable thereby; means operatively connected to and actuated by the filling detector for moving the rod of said linkage when the filling detector detects a spent bobbin at the box side of the loom; said rod when moved by said last-mentioned means causing said linkage to move from an inactive position to second position; and means movable by said lay and engageable with the actuating arm fixed to said cam when the same has been moved to the second position to thereby cause said hammer to pivot about its axis and insert a full bobbin in the shuttle while stripping a spent bobbin therefrom.

6. The automatic replenishing loom as claimed in claim 5 in which said means operatively connected to and actuated by the filling detector for moving the rod of said linkage includes a first electrical circuit having a relay therein, a normally open switch in said circuit and operatively connected to the filling detector, said switch being closed upon detection of a spent bobbin, a holding circuit for said relay, a second circuit normally open and having a solenoid therein, said second circuit being closed upon energizing of said relay, said solenoid in said second circuit being operatively connected to said rod for moving the same.

7. The automatic replenishing loom as claimed in claim 6 including means for short circuiting said holding circuit

when the hammer is actuated, said means including a normally open switch in parallel with said relay, said last-mentioned switch being operatively connected to and closed upon actuation of the hammer.

8. The automatic replenishing loom as claimed in claim 5 7 including means to short circuit said holding circuit when said loom is stopped, said means including a normally open switch in parallel with said relay and also in parallel with the switch of said first mentioned short circuiting means, said last-mentioned switch being closed 10 upon stoppage of said loom.

9. The automatic replenishing loom as claimed in claim 5 in which said means movable by the lay includes a duck-

bill operatively positioned to engage the actuating arm of said linkage means when the same is in the second position.
